ARC LAMP

James H. Wagenhorst, Jackson, Mich.

Application October 13, 1928. Serial No. 312,326

14 Claims. (Cl. 176—58)

My invention relates to improvements in arc lamps and has to do, more particularly, with certain improvements in the design and construction of such lamps, which adapt them for use in giving therapeutic treatments in the home. The present invention comprises certain improvements over the arc lamps shown and claimed in my Patents, Number 1,817,955, filed March 4, 1926, and Number 1,884,417, filed Jan. 31, 1928.

10 The principal object of my invention is to provide an arc lamp of such construction as to be very simple and efficient and which will operate smoothly and effectively. Another object of my invention is to provide an arc lamp construction in which all chattering due to the use of alternating current is eliminated. A further object of my invention is to provide improved and simple means for retarding the movement of the electrodes, in the direction to draw the arc, while 15 leaving the electrodes free to move toward each other when the arc has been extinguished. Another object of my invention is to provide an improved means by which the electrodes can be straightened and aligned, after they have been 20 clamped in the electrode holders. A further object of my invention is to provide an arc lamp construction which will have a greater effective light output due to the fact that the crater of the 25 arc is exposed so that both the flame and the spot of the arc are effective. A further object of my invention is to provide an improved cabinet construction and, further, a cabinet provided with means for preventing sparks from falling from 30 the cabinet to the floor of the room in which the 35 lamp is used.

Further objects, and objects relating to details and economies of construction and operation will definitely appear from the detailed description to follow. In one instance, I accomplish the objects of my invention by the devices 40 and means set forth in the following specification. My invention is clearly defined and pointed out in the appended claims. A structure constituting a preferred embodiment of my invention 45 is illustrated in the accompanying drawings, forming a part of this specification, in which

Figure 1 is a perspective view of an arc lamp embodying my invention;

50 Fig. 2 is a view of the lamp and operating mechanism in front elevation, a portion of the cabinet and the housing for the mechanism being shown in section;

55 Fig. 3 is a detail, sectional view, taken on the line 3—3 of Fig. 2;

Fig. 4 is a detail, sectional view taken on the line 4—4 of Fig. 2;

Fig. 5 is a top plan view of the lamp, with the housing surrounding the operating mechanism shown in section;

60 Fig. 6 is a detail, sectional view through the holder for the upper electrodes, taken on the line 6—6 of Fig. 2;

Fig. 7 is a detail, sectional view showing the connections between the upper end of the clutch-operating rod and the clutch-operating lever, taken on the line 7—7 of Fig. 2;

Fig. 8 is a detail, sectional view showing the mounting for the lower electrodes, taken on the line 8—8 of Fig. 2;

70 Fig. 9 is a wiring diagram showing the electrical connections for the lamp;

Fig. 10 is a detail, sectional view showing the means for holding the adjustable reflector or front wall of the cabinet in adjusted position, and

75 Fig. 11 is a detailed perspective view showing the clutch.

In the drawings, the same reference numerals refer to the same parts throughout the several views and the sectional views are taken looking 80 in the direction of the arrows at the ends of the section lines.

One of the objects of my invention is to eliminate the chattering of the electrodes due to the use of alternating current and I accomplish this 85 object by providing a resilient support for the solenoid, the solenoid being supported by spring arms carried by the frame. I have provided a brake for retarding the movement of the operating mechanism which draws the arc, so as to 90 slow up this movement. I have found that this brake is simpler than a dash-pot and that it has the advantage that it retards movement only in the one direction. I have provided a saddle 95 swiveled on one of the electrode holders and have found that this permits the carbons or electrodes to be straightened and lined up after they have been clamped in the holders. My invention comprises also the mounting of the electrodes in the frame, and the suspension of the frame, in such a way that the electrodes are inclined slightly from the vertical and lean backward. I have found that this exposes the crater of the arc, so 100 that both the flame and the spot of the arc are effective to give light. I have also provided an improved and simple cabinet construction as will be seen hereinafter.

105 Referring to the particular embodiment of my invention illustrated in the accompanying drawings, I have shown an arc lamp the electrodes

of which are suspended and supported from a frame 10, which is formed from a bar or strip bent into rectangular form and provided with two parallel tail members 11 extending from the 5 central portion of the base of the rectangular frame. These tail members 11 serve to support the lower or stationary electrodes of the arc lamp. A block 12, of insulating material, is fastened to these tail members 11 by bolts 13, 10 and an electrode supporting bar 14 is fastened to the block 11 by the bolts 15. The bar 14 extends transversely of the lower portion of the lamp within the cabinet and has, at opposite ends, a pair of grooves 16, which are adapted 15 to receive the electrodes 17. The electrodes are clamped in position on this bar by the clamping plates 18 and the bolts 19, as shown more particularly in Fig. 8. In this way, the lower or stationary electrodes are so mounted that four 20 of them can be clamped substantially parallel to each other. Referring to Fig. 8, it will be seen that the radius of each groove 16 is considerably less than the radius of the carbon 17. By using grooves of this formation, I can clamp carbons 25 of varying diameter in the same holders. This is of advantage because differences in current used sometimes require a slight variation in the size of the carbons employed.

To each side member of the frame 10, there 30 are fastened slabs 20 of insulating material and at the bottom, near the lower ends of these slabs, the angle brackets 21 are fastened. These brackets have horizontal legs provided with openings through which the movable electrodes 22 extend. These movable electrodes, as well as the corresponding stationary electrodes, are arranged in pairs, one pair on each side of the center of the lamp. Each pair of movable electrodes 22 co-operates with an electrode holder 35 comprising a plate 23, having, at one side, a groove 24 receiving one of the electrodes 22, while the other part of the plate is offset at 26, and has a saddle 25 swiveled thereto by rivet 26', which saddle receives the other electrode. 40 The electrodes are clamped in this holder by clamping plate 29, which engages the opposite sides of the electrodes and is clamped against the holder by bolt 30. The groove 24 and the saddle 25 are formed, as in the case of the lower 45 carbons, so as to permit of the clamping of electrodes of varying diameter in the same holders. An angle bracket 27, the upper end of which is bent laterally at 33 and has an opening therethrough through which the clutch operating rod 50 moves, is fastened to the holder by bolt 30, washers 28, of insulating material, being mounted on the bolt on opposite sides of the bracket 27 to insulate the same from the carbon holder. The guiding brackets 33 which slide on the clutch 55 operating rod 34, insure the accurate alinement of the upper and lower electrodes. These electrodes are guided at the points where they pass through the bracket 21 and by the sliding contact of the rods 34 with the edges of the openings 60 in the guide brackets 33. These points are spaced a considerable distance apart, as will be seen from Fig. 3. Of course, a considerable clearance has to be provided in the holes in the guide brackets 21, to permit the electrodes to slide 65 through them easily and this clearance has the tendency to throw the upper electrodes out of alinement with the lower electrodes as they are fed downwardly. However, due to the guide arms 70 33, the guiding points are kept far enough apart 75 to insure true alinement of upper and lower elec-

trodes at all points in their feed. The terminal 80 31 of circuit lead 32 may be inserted beneath the head of the bolt 30 in order to make electrical connection between this lead and the electrode holder. There are two electrode holders of this construction provided, one for each pair of the upper or movable electrodes, and these holders hold the electrodes clamped in parallel relation to each other. The saddle 25 permits a slight swiveling of the electrode which is clamped in it and this permits the electrodes to be straightened and alined more conveniently after they have been clamped in the electrode holder.

85 Each pair of movable electrodes is provided with a clutch and clutch-operating mechanism by which these electrodes may be raised and lowered with reference to the lower or stationary electrodes, in order to draw an arc. Each clutch comprises a flat strip bent into a U-shaped form having the bight 38 of the loop embracing one of the electrodes, so as to clamp the same when tilted, while the legs 38' of the clutch member lie on opposite sides of the other electrode. A clutch-operating rod 34 extends through the 90 guide hole in the portion 33 of bracket 27 fastened to the electrode holder, and the lower end of this clutch rod is bent laterally, at 35, and then again, at right angles, at 36, to form a portion which extends through both legs 38' of the U-shaped clutch member and is held in place with respect thereto by cotter pins 37. The clutch member lies just above and cooperates with the horizontal portion of the corresponding bracket member 21, as clearly shown in Fig. 11. The upper end of each clutch-operating rod 34 is connected by a swivel or pivot connection with one of the two clutch-operating levers 39. The inner ends 40 of these levers cross each other and the levers are pivoted on the side members of the 95 frame 10, at 41. The shape of the clutch-operating levers is best shown in Fig. 5, and it will be seen that each comprises a flat strip bent into U-form and having one leg longer than the other and constituting the inner end of the lever which 100 crosses the corresponding inner end of the other lever. One of these longer legs is provided with a slot 54' in which a bolt 55', carried by the corresponding leg of the other lever, works in order to provide a pin and slot connection between the 105 crossing ends of the clutch-operating levers. In Fig. 7, I have shown the connection between the upper end of a clutch-operating rod 34 and the corresponding outer end of the clutch-operating lever 39. A nut 42 is mounted on the upper end 110 of the rod 34, and held in position thereon by the lock nuts 44 threaded on the rod 34 above and below nut 42, and the washers 43, of insulating material, interposed between the nut 42 and the lock nuts 44, so that the nut 42 is held adjustably 115 fixed with reference to the upper end of the clutch-operating rod 34. The nut 42 is swiveled to the outer end of the operating lever, which straddles it, by a cross pin 45, which extends through the nut and through the legs of the operating lever, as shown in Fig. 7.

120 The clutch-operating levers 39 are controlled by a solenoid 46, which is mounted in a resilient manner within the rectangular frame 10. The solenoid 46 is clamped between end plates 47, 125 48, which are held together by the clamping rods 49. The springs 49 are fastened to the inner side of the side member of the frame 10, at 50, and have laterally extending spring arms 51 fastened to the ends of the end plates 47. These 130

80

125

130

135

140

145

150

spring arms provide a resilient support for the solenoid 46. The laminated core 52, which works within the solenoid, has the laminations divided and the end portions turned laterally, as at 53, providing two oppositely extending arms connected by coil springs 54 with the levers 39, the upper ends of said springs being hooked into the levers at 55. In this way, there is a resilient connection between the core and the clutch-operating levers and a resilient support for the solenoid, and I have found that this arrangement is very effective to prevent chattering of the electrodes due to fluctuations in the current passing through the solenoid.

In order to damp and check the movement of the clutch-operating levers, when moving in a direction to draw the arc, I have provided, instead of the usual dash-pot, a brake mechanism which I have found particularly effective for this purpose. A brake shoe 56 is provided with a pair of ears 57 straddling one side member of the frame 10 and secured thereto by the pivot pin 58. A facing 59, of braking material, is applied to this shoe. A brake strap 60 cooperates with this brake shoe. The lower end of this brake strap is loosely embraced by a loop 61 mounted on a side member of the frame. The upper end of the brake strap has an eye 62 to which is fastened one end of a link 63, the other end of said link being turned laterally and projecting through the legs of the corresponding operating lever 39. It will be seen that, with this arrangement, when the operating levers are moved in a direction to draw the arc, that is, to lift the movable electrodes, the link 63 will draw the braking strap 60 into contact with the braking material 59 and retard the motion of the lever, while, when the levers move in the other direction, to permit the electrodes to approach each other, the link 63 will cause the strap to move away from the brake shoe so that there will be no retardation of the corresponding movement of the operating levers.

The wiring diagram illustrating the electrical connections of the arc lamp is shown in Fig. 9. One terminal to which one of the main circuit wires is connected is shown at 66, and this terminal is connected with the solenoid 46 by the connecting wire 65. From the other end of the solenoid 46, a connecting wire 32 leads to the electrode holder for the right hand pair of upper or movable electrodes. The circuit leads from the terminal 66, therefore, through the wire 65, solenoid 46, wire 32 and the right hand electrode 22 to the corresponding lower electrode and, thence, by the bar 14 to the left hand electrode 17, the left hand upper electrode 22, and the left hand electrode holder, and, thence, through the wire 67 to a terminal 68. The terminal 68 is connected to the lower end of a resistance coil 69 mounted on the right hand block 20 of insulating material. The upper end of this coil is connected by wire 70 with a corresponding coil 71 mounted on the left hand slab 20 of insulating material, and the circuit is from the terminal 68, through the resistance coils 70 and 71 to the terminal 72, to which the other main circuit wire is connected. It will be observed, therefore, that, whenever the circuit just described is closed, the solenoid will be energized to attract its armature and depress the inner ends of the clutch-operating levers 39, thus raising the carbons and causing the movable electrodes to separate from the lower electrodes. Whenever this circuit is broken, however, as by the extinguishment of the arc drawn between the

upper and lower electrodes, the solenoid will be de-energized and the weight of the suspended electrodes will cause the clutch-operating levers to lift the core 52 and thus permit the upper electrodes 22 to move into contact once more with the lower electrodes to re-establish the circuit.

The particular frame arrangement and the mounting for the electrodes, and the operating mechanism therefor, are particularly advantageous, since they balance the lamp laterally as well as fore and aft, reduce the lamp's size, and insure better and more uniform lighting. The frame 10 constitutes the backbone of the lamp and is centrally located. Due to the insulating block 12, the lower electrodes are mounted slightly in front of the frame 10. The insulating boards 20 afford supports for the brackets 21, through which the upper electrodes slide, in alignment with the lower electrodes. These insulating boards 20 extend fore and aft of the lamp and are so arranged with the resistance coils 69 and 71 thereon that the heat from the resistance coils is baffled and prevented from reaching the solenoid 46, which is located between the two insulating boards. Cool air passing through the opening 97 in the housing 86, which surrounds the operating parts, passes up around the solenoid and the resistance coils and out through the openings 89. This frame 10 not only acts as the backbone of the lamp, but also supports the cabinet and the housing for the operating mechanism. The tail member 11 of this frame extends downwardly through an opening in the bottom wall of the reflector or cabinet 75 and this projecting lower end of the tail member 11 may be inserted in a tubular socket upon a supporting stand, so that the lamp may be supported either from a floor stand or from an overhead suspension, as hereinafter described.

The lower ends of the upper electrodes 22 and the lower electrodes 17 are located within a housing 73, the top wall of which is secured to the lower portion of the frame 10 by the bolts 74. Holes are provided in the top wall of this housing through which the electrodes 22 and the tail members 11 of the frame extend, the latter affording a support for the lower electrodes within the housing. This cabinet is formed of suitable material and so shaped as to serve as a reflector for the light developed by the arc formed between the adjacent ends of the upper and lower electrodes. To this end, the rear wall 75 is suitably curved along parabolic lines. The front edge of wall 75 has a flange 76 curved forwardly to form a trough, which catches any sparks falling upon the bottom wall of the housing and prevents them falling from the open front of the cabinet to the floor of the room in which the lamp is used. The side walls 77 of the housing are extended beyond the front edges of the top and bottom walls, as best shown in Fig. 3. The front of the housing is closed by a movable front wall 78, having side walls 79 connected thereto which overlap the side wall extensions 77. The front wall is adjustably fixed with reference to the housing, as by the brackets 80, secured to the side wall 79 by the rivets 81, and having portions 82 bent back against the inner face of the side wall 77. Thumb screws 83 extending through the side walls 79 and the brackets 80, serve to clamp the side wall 77 against the turned back portion 82 of the bracket, and to hold the movable front wall 78 in adjusted position. By adjusting this front wall 78 back

and forth the light emanating from the arc can be directed as necessary in the use of the lamp. The front wall 78 is hinged to the housing by ears 84 at the rear upper end of the front wall, 5 which are hinged to projecting ears on the housing by the pivot bolts 85, as shown in Figure 1. The rear edge of the upper wall 78 is bent inwardly at 78' so as to provide a ventilating slot at the top of the reflector or cabinet through 10 which the hot air and fumes coming from the arcs may escape at the top of the reflector.

This movable front wall 78 provides a cabinet having an opening of variable dimensions through which the light is directed. The direct 15 light rays both from the craters of the upper electrodes as well as the flames of the arcs, are directed downwardly at an angle of about 45°. The cabinet is so designed that the reflected light emanating from the flames and craters of the arcs 20 is directed through the main opening of the cabinet. The lower stationary portion reflects the light of the craters through the main light outlet. The movable upper wall 78 of the reflector confines the light to a variable area dependent on its position, so that all the light can 25 be concentrated on a small or large area. Thus, a doctor can treat his patient without subjecting himself to the intense rays of light, or a photographer can, by adjusting the front wall 78, 30 determine the area which he will illuminate with the lamp and thus secure the variable lighting effects much sought after in the modern photographic art. If it is desired to soften the light, for photographic or other purposes, a diffusing 35 screen may be arranged and drawn tight over the open front end of the reflector cabinet.

The operating mechanism of the lamp is covered by a housing 86 mounted upon the top of the reflector, as shown in Figure 1. A saddle 40 member 87 is fastened by rivet 88 to the inner top surface of housing 86 and loosely embraces the top member of the frame 10. This saddle serves to center the housing 86 with reference to the operating mechanism and makes sure that it 45 is properly applied so as not to interfere with any of the working parts. Angle brackets 90 are riveted to the housing 86 near the bottom of the side walls thereof, as shown in Fig. 2. The horizontal portions of these brackets lie upon the top 50 wall of the reflector 73. These horizontal portions of the brackets 90 are provided with slots 91, which receive the bolts 92 by which the brackets 90 are clamped to the top wall of the reflector housing. Openings 89 in the upper corners of 55 the housing 86 permit the circulation of air through the housing to cool the operating parts. This circulation is aided by the opening 97 formed in the central lower front portion of housing 86, which also permits the suspending arm to pass 60 to the outside of the housing, as shown in Figure 1.

A bar 93 is inserted between the tail members 11 of the frame and fastened in position there, as shown in Fig. 2. This bar is offset forwardly, at 94, and then extends upwardly, at 95, to form 65 a suspending arm. A pulley 96 is fastened to the upper end of this arm, through which runs a cable by which the apparatus may be suspended from the ceiling or a supporting bracket. This suspending arm 95 is located at such an angle 70 that, when the apparatus is suspended by a pulley, as shown in Fig. 3, the electrodes will not be in true vertical alinement but will be alined in a plane tilted backward slightly from the vertical. The result of this is that a more efficient discharge 75 of light is secured in that the crater formed at

the cooperating ends of the electrodes does not tend to hide any of the light emanating from the hot spot at the meeting ends of the electrodes. By tilting the electrodes slightly from the vertical in this way, the crater is so formed that it opens 80 slightly toward the front of the reflector housing and thereby the light is permitted to emanate directly from the crater through the open mouth of the housing and it is not concealed or interrupted by the walls of the crater.

I am aware that the particular embodiment of my invention illustrated in the accompanying drawings, and here described, may be varied considerably without departing from the spirit of my invention, and, therefore, I claim my invention broadly as indicated by the appended claims.

What I claim is:

1. In an arc lamp, the combination of a frame, a stationary electrode supported by the frame, a movable electrode cooperating with the stationary electrode to form an arc, a solenoid, yokes clamped to the top and bottom of said solenoid, a pair of coil springs carried by the frame and each having a pair of laterally extending arms secured to opposite ends of the adjacent yoke to 100 yieldingly support said solenoid, a movable core for said solenoid, a clutch cooperating with the movable electrode and connections between said core and clutch.

2. In an arc lamp, the combination of a frame 105 including a pair of upright portions, a stationary electrode supported by the frame, a movable electrode cooperating with the stationary electrode to form an arc, a solenoid resiliently supported from one only of said upright portions of the 110 frame, a movable core for said solenoid, a clutch cooperating with the movable electrode, and connections between said core and clutch including a resilient link.

3. In an arc lamp, the combination of a stationary electrode, a movable electrode cooperating therewith to form an arc, a clutch for said movable electrode, operating means for said clutch, a braking surface, and a brake member connected with said means and movable thereby 115 into and out of braking engagement with said surface.

4. In an arc lamp, the combination of a stationary electrode, a movable electrode cooperating therewith to form an arc, a clutch for said movable electrode, a clutch operating lever, a braking surface, and a brake member connected with said lever and movable thereby into and out of braking engagement with said surface.

5. In an arc lamp, the combination of a stationary electrode, a movable electrode cooperating therewith to form an arc, a clutch for said movable electrode, a clutch operating lever, a braking surface, and a brake member connected with said lever and brought into braking engagement 130 with said surface when the lever is actuated to move the movable electrode and draw the arc.

6. In an arc lamp, the combination of a frame, a stationary electrode, a movable electrode, a clutch cooperating with said movable electrode, a braking surface mounted on the frame, a clutch operating lever pivoted on the frame, a brake member adapted to engage said surface, and a link connecting said member and said lever.

7. In an arc lamp, the combination of a frame, 145 a stationary electrode, a movable electrode, a clutch cooperating with said movable electrode, a braking surface mounted on the frame, a clutch operating lever pivoted on the frame, a rod connecting said lever and clutch, a brake member 150

adapted to engage said surface and a link connecting the upper end of said member and the lever between the latter's point of connection with the rod and its pivot.

5 8. In an arc lamp, the combination of a frame, a stationary electrode, a movable electrode, a clutch cooperating with the movable electrode, a clutch operating lever pivoted on the frame, actuating means connected to the inner arm of said lever, a rod connecting the outer arm of said lever and the clutch, a brake shoe mounted on the frame, a brake strap cooperating with the shoe, and a link connecting the upper end of said strap and the outer arm of said lever.

15 9. In an arc lamp, the combination of a frame, a stationary electrode, a movable electrode, a clutch cooperating with the movable electrode, a clutch operating lever pivoted on the frame, actuating means connected to the inner arm of said lever, a rod connecting the outer arm of said lever and the clutch, a swiveled brake shoe mounted on the frame, a brake strap cooperating with the shoe, and a link connecting the upper end of said strap and the outer arm of said lever.

20 10. In an arc lamp, the combination of a frame, a stationary electrode, a movable electrode, a clutch cooperating with the movable electrode, a clutch operating lever pivoted on the frame, actuating means connected to the inner arm of said lever, a rod connecting the outer arm of said lever and the clutch, a swiveled brake shoe mounted on the frame, a brake strap cooperating with the shoe, and a link connecting the upper end of said strap and the outer arm of said lever.

25 11. In an arc lamp, the combination of a frame, a stationary electrode, a movable electrode, a clutch cooperating with the movable electrode, a clutch operating lever pivoted on the frame, actuating means connected to the inner arm of said lever, a rod connecting the outer arm of said lever and the clutch, a brake shoe having a pair of laterally extending flanges located on opposite sides of a frame member, a horizontal pin pivotally connecting said shoe to the frame and extending through said flanges, friction material carried by the base of said shoe, a brake strap cooperating with the friction material of said shoe, and a link connecting the upper end of said strap and the outer arm of said lever.

30 12. In an arc lamp, the combination of a frame, a stationary electrode, a movable electrode, a clutch cooperating with the movable electrode, a clutch-operating lever pivoted on the frame, actuating means connected to the inner arm of said lever, a rod connecting the outer arm of said lever and the clutch, a brake shoe mounted on the

frame, a brake strap cooperating with the shoe, a link connecting the upper end of said strap and the outer arm of said lever, and a yoke fixed to the frame and embracing the lower end of said strap.

35 12. In an arc lamp, the combination of a frame, a stationary electrode, a movable electrode, a clutch cooperating with the movable electrode, a clutch-operating lever pivoted on the frame, actuating means connected to the inner arm of said lever, a rod connecting the outer arm of said lever and the clutch, a swiveled brake shoe mounted on the frame, a brake strap cooperating with the shoe, and a link connecting the upper end of said strap and the outer arm of said lever, and a yoke fixed to the frame and embracing the lower end of said strap.

40 13. In an arc lamp, the combination of a frame having a pair of upright members, a pair of stationary electrodes, a pair of movable electrodes, a pair of clutches cooperating therewith, a U shaped lever having a long and a short leg straddling, and pivoted to one upright frame member, the short leg terminating adjacent the pivot, the long leg extending inwardly beyond the pivot, a similar lever disposed upon the other upright member, the long leg of each lever being an alignment with the short leg of the other lever, whereby the long legs of the levers are disposed in side by side relation, a link connecting the outer end of each lever to its respective clutch, a solenoid, a core for the solenoid, and connections between said core and the long legs of the levers.

45 14. In an arc lamp, the combination of a frame including a pair of upright portions, a stationary electrode supported by the frame, a movable electrode cooperating with the stationary electrode to form an arc, a pair of spring arms carried by and extending laterally from one of said upright portions of the frame, a solenoid inserted between and supported by said arms whereby said solenoid is yieldingly supported from the frame, a movable core for said solenoid, a clutch cooperating with the movable electrode and connections between said core and clutch.
